(57) **CLAIM**

We claim the ornamental design for portion of a power module for power inverter, as shown and described.

DESCRIPTION

FIG. 1 is a front, top and right side perspective view of portion of a power module for power inverter showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown are for illustrative purpose and form no part of the claimed design. The alternate long and short dash lines define, but are not included in, the boundaries of the claimed design.
